(57) CLAIM

The ornamental design for a headboard caddy, as shown and described.

DESCRIPTION

FIG. 1 is a front top left perspective view of a headboard caddy, showing my new design;

FIG. 2 is a front elevation view thereof;

FIG. 3 is a left-side elevation view thereof, the right-side elevation view being a mirror image thereof;

FIG. 4 is a rear elevation view thereof;

FIG. 5 is a top plan view thereof; and,

FIG. 6 is a bottom plan view thereof.

The evenly sized (dash-dash) broken lines shown in the drawings depict portions of the headboard caddy that form no part of the claimed design.

The unevenly sized (dash-dot-dash) broken lines shown in the drawings depict the bounds of the headboard caddy and form no part of the claimed design.

The headboard caddy is shown a symbolic break in its length. The appearance of any portion of the article between the break lines forms not part of the claimed design.
